[57] CLAIM

The ornamental design for a wood spice rack, as shown and described.

DESCRIPTION

FIG. 1 is a front perspective view of a wood spice rack showing our new design; the bottle shown in broken lines for illustrative purposes only.

FIG. 2 is a rear elevational view thereof, taken along lines 2—2 of FIG. 6;

FIG. 3 is a right side elevational view thereof, taken along lines 3—3 of FIG. 6;

FIG. 4 is a front elevational view thereof, taken along lines 4—4 of FIG. 6;

FIG. 5 is a bottom plan view thereof; and

FIG. 6 is a cross sectional view thereof, taken along lines 6—6 of FIG. 1.
